To all whom it may concern:

Be it known that I, Michael Annick, a citizen
of the United States residing at 617 Harrison
Avenue, in the city of Scranton, county of Lacka-
wanna, State of Pennsylvania, have invented a
new, original, and ornamental Design for a Vacu-
um Printing Frame, of which the following is a
specification, reference being had to the accom-
panying drawing, forming part thereof.

The figure is a perspective view of a vacuum
printing frame, showing my new design.

I claim:

The ornamental design for a vacuum printing
frame, as shown.

MICHAEL ANNICK.
